UNITED STATES PATENT OFFICE.

WARREN D. REIST, OF WILLIAMSVILLE, NEW YORK.

DESIGN FOR A CROCHET-STAND.

46,137.

Specification for Design.

Patented July 21, 1914.

Application filed April 29, 1914. Serial No. 835,319. Term of patent 14 years.

To all whom it may concern:

Be it known that I, WARREN D. REIST, a citizen of the United States, residing at Williamsville, in the county of Erie and State of New York, have invented a new, original, and ornamental Design for Crochet-Stands, of which the following is a specification, reference being had to the accompanying drawing, forming part thereof.

The figure is a perspective view of the crochet stand.

I claim:

The ornamental design for crochet stand, as shown.

WARREN D. REIST.

Witnesses:

MAUDE B. COX,
CLARA A. WALTER.
